US00D679709S

(12) **United States Design Patent**
Hayes et al.

(10) **Patent No.:** US D679,709 S
(45) **Date of Patent:** ** Apr. 9, 2013

(54) **BOOK SCANNING DEVICE CAMERA ASSEMBLY AND PAGE COMPRESSOR**

(75) Inventors: **Jonathan Hayes**, Boston, MA (US);
Paul Williamson, Providence, RI (US)

(73) Assignee: **inMusic Brands, Inc.**, Cumberland, RI (US)

(**) Term: **14 Years**

(21) Appl. No.: **29/389,025**

(22) Filed: **Apr. 6, 2011**

(51) **LOC (9) CL.** 14-02

(52) **U.S. CL.**

USPC **D14/421**

(58) **Field of Classification Search** D14/420-424,

(57) **CLAIM**

The ornamental design for a book scanning device camera assembly and page compressor, showing our new design as shown and described.

DESCRIPTION

FIG. 1 is a top, front, and left side perspective view of an embodiment of a book scanning device camera assembly and page compressor showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a perspective view of the book scanning device shown in use.

Broken lines and portions contained within broken lines are not claimed.

1 Claim, 8 Drawing Sheets
